UNITED STATES PATENT OFFICE.

WALTER ZEHNDER, OF GRANICHEN, SWITZERLAND.

ELECTROMAGNETIC CHUCK.

Application filed October 5, 1921, Serial No. 505,677.

To all whom it may concern:

Be it known that I, WALTER ZEHNDER, citizen of the Republic of Switzerland, residing at Granichen, Switzerland, have invented certain new and useful Improvements in Electromagnetic Chucks, of which the following is a specification, reference being had therein to the accompanying drawing.

This invention relates to improvements in electromagnetic chucks and particularly to improvements in the plate for holding work pieces of electromagnetic chucks.

Most of the troubles with electromagnetic chucks arise from short circuits which originate from the fact that during the wet working of a blank the liquid, for instance the cooling water, penetrates through the intermediate spaces between the pole pieces or between the pole pieces and the tightening material which is inserted between the pole pieces and passes into the interior of the electromagnetic chuck and gets in contact with the magnet coils. Electromagnetic chucks working with direct current are especially subjected to this danger because it is impossible to bring the non-magnetic material inserted in the magnetic plate, for instance the cast-in metal such as zinc, into intimate contact with the iron and to maintain an intimate contact of that metal with the iron of the pole pieces. Therefore, after a short working period an appreciable air gap presents itself between the tightening material and the pole pieces through which gap the liquid leaks into the interior of the chuck. The heating up of the magnetic plate contributes also to that leakage. With chucks worked with alternating current where metal cannot be cast in the spaces between the pole pieces for reasons due to the nature of the current, non-magnetic material such as gutta-percha, rubber, fibre and the like have been pressed in between adjacent pole pieces. But also in this case gaps were soon formed and the tightening material got detached from the iron of the pole pieces on account of chemical, hygroscopic and thermal influences. The utilization of electromagnetic chucks of the above described type prevented therefore the wet working of blanks, such as for instance wet-grinding of pieces held by such a chuck.

The object of the present invention is a plate for holding work pieces in electromagnetic chucks comprising a plurality of

pole pieces arranged side by side and non-magnetic material being inserted between the pole pieces and in which plate the above mentioned disadvantages are overcome by arranging the pole pieces together with the tightening material inserted between them in a frame chuck and pressing them tightly together and fixing them to said frame in their pressed state. In chucks worked with direct current the pole pieces may consist of a single piece of iron, for instance of a cast steel body, and the intermediate spaces between two adjacent pole pieces may be filled up with brass sheets. With electromagnetic chucks worked with alternating current the pole pieces are built up of laminated dynamo sheets and the intermediate spaces are filled up by a non-magnetic and non-conducting material.

Several embodiments of the invention are shown by way of example on the accompanying drawings, in which:

Fig. 1 is a section through a first constructional example along line I—I of Fig. 2;

Fig. 2 is a plan view in which part of the plate is broken off;

Fig. 3 is a cross-section along line III—III of Fig. 1;

Fig. 4 shows a modification of a detail;

Fig. 5 is a section of another constructional example along line VI—VI of Fig. 6;

Fig. 6 is a plan view with part of the top plate broken off; and

Fig. 7 is a cross-section along line VIII—VIII of Fig. 6.

Referring to the Figs. 1-3 two longitudinal bars 2 are rigidly fixed by means of set screws 3 to the upper part of the chuck casing 1 that is open at its top. The sides of the two bars pointing towards each other are V-shaped and bars 4 of angle cross section and made of a non-magnetic material are inserted into said V-shaped sides of the bars 2. A cross piece 5 is inserted at each end of the bars 2 between said bars and screwed to the casing 1 by means of set screws 6. At the inner side of each cross piece 5 and at certain intervals, separating or spacing plates 7 of non-magnetic material are provided, between which a number of dynamo plates forming together a pole piece 8 are arranged. Below each pole piece thus formed a magnet core 13 is situated provided with a coil 9. The pole pieces 8 are thus spaced from each other by the plates

7 of non-magnetic material and the whole space between the two longitudinal bars 2 or the bars 4 respectively and the two cross pieces 5 are thus alternately filled with separating plates 7 and pole pieces 8. Previous to the second cross piece 5 being inserted and fixed a very powerful pressure is exerted upon the plates 7 and the pole pieces 8 and then to the cross piece 5 after it has been brought in position a strong pressure in the direction towards the already fixed other cross piece 5 is applied whereafter the plates 7 and the dynamo sheets 8 are held tightly pressed together by the cross pieces. Then the second cross piece 5 is secured to the casing 1 by means of set screws 6 entering tapped holes 10 of the casing 1. Set screws 11 for fixing the longitudinal bars 2 to the cross pieces 5 serve to hold the tightly pressed parts together.

The magnets 9 are formed by the coils 12 arranged around the cores 13. The latter are also built up of laminated dynamo sheets and form together with the yoke 14 one unit as may be seen from Fig. 1. Between the ends of the cores 13 and the pole pieces 8 there is provided a small intermediate space of approximately $\frac{1}{2}$ mm. width for permitting of the extension of the parts caused by the heating and for facilitating erection. The dynamo sheets forming the cores 13 and the yoke 14 are held together between the end sheets 16 and clamping pieces 17 by means of screw bolts 15. The bolts 15 are paper insulated. Between the inner sides of the longitudinal bars 4 and the inserted dynamo sheets 8 an insertion 22 of paper is provided in order to prevent short circuits between the dynamo sheets at the sides thereof. This insertion 22 serves at the same time as tightening material. The yoke is held in a frame 23 secured to the bottom of the casing 1 by set screws 24.

It is not necessary that the dynamo sheets 8 forming the pole pieces have the shape illustrated in Fig. 3 but they may also be integral with the cores or with the dynamo sheets of which the cores are formed as is shown in Fig. 4. In this case the dynamo sheets are held together by bolts arranged in the longitudinal direction of the chuck instead of the bolts 15 arranged in the transverse direction as shown in Fig. 3. To this end holes 19 (Fig. 4) are provided in the dynamo sheets. The dynamo sheets situated between the sets of sheets forming each core are not provided with the downward extension as illustrated in Fig. 4 but are of the same shape as the dynamo sheets 8 in Fig. 3. The sheets 18 abut against a common yoke 14 which is built up of dyna-

mo sheets extending in the longitudinal direction of the chuck.

Further it is not necessary to hold the intermediate or the spacing parts 7 and the pole pieces 8 together by a frame.

As is illustrated in Figs. 5-7 the pole pieces 8 may also be narrower than the thickness of the cores. The bundles of dynamo sheets 8 of which each pole piece is built up are interposed between a number of spacing plates 7 of non-magnetic material. The single pole pieces is of small extension in this case. This construction is especially suited for holding small work pieces, as in order to be held by the chuck a work piece has to bridge over and connect magnetically two pole pieces 8 separated by an intermediate plate 7. In this constructional example the yoke 14 is clamped in between two longitudinal supporting beams 25 which are suspended from the plate consisting of the pole pieces 8 and the intermediate parts 7 by means of screw bolts 26.

In the chucks according to the invention no gaps between the pole pieces and the spacing material can form themselves and these chucks are therefore particularly suited for the wet-working of work pieces.

I claim:

1. In an electromagnetic chuck, a flat, composite plate composed of sets of laminations of dynamo sheet alternating with non-magnetic material, said laminations arranged transversely of the flat plate, said plate having opposite wedge-shaped edges, means at the ends of the plate to hold the composite plate compressed with a force sufficient to prevent the passage of water between the laminations under all conditions of expansion and contraction incident to the use of the chuck, and longitudinal bars having V-shaped recesses in which the wedge-shaped edges of the plate fit and are held watertight.

2. In an electromagnetic chuck, a casing open at its top, a work-holding composite plate forming a cover for said casing and consisting of groups of vertical laminations alternating with non-magnetic material arranged transversely of said plate and having wedge-shaped ends, means secured to said casing to maintain the laminations of the plate under compression, longitudinal bars having V-shaped slots into which the wedge-shaped ends of the laminations fit, said bars secured to said means and the casing, laminated magnet-cores in the casing beneath said plate, windings on the cores and a yoke member for the cores.

In testimony whereof I affix my signature.

WALTER ZEHNDER
